Primary Examiner — Ricky Pham

(57)

CLAIM

The ornamental design for coffee roaster, as shown and described.

DESCRIPTION

1. Coffee roaster

1.1 : Front

1.2 : Back

1.3 : Top

1.4 : Bottom

1.5 : Right

1.6 : Left

1.7 : Perspective

1.8 : Reference view of state in use (1)

1.9 : Reference view of state in use (2)

The parts shown by means of broken lines in the reproductions are not part of the claimed design. Cans containing coffee beans etc. are gripped between holding arms of the roaster and heated over a heat source. The roaster can change the opening angle of support legs, as well as the height and angle of the holding arms, depending on the heat source. A crank handle is provided to rotate the cans manually so as to

(Continued)

heat the cans evenly. The parts shown by means of broken lines in the reproductions are not part of the claimed design.

1 Claim, 9 Drawing Sheets
